DOOR CONTROLLING MECHANISM

Charles F. Sponsler, Philadelphia, Pa.

Application June 5, 1931, Serial No. 542,448

13 Claims. (Cl. 268—62)

This invention relates to door controlling mechanism for simultaneously opening or closing a pair of swinging or hinged doors by manually swinging one of them in the desired direction.

The principal objects of the invention are: to provide simple, reliable and efficiently operating means for communicating swinging movement to one of a pair of hinged doors when the other door is opened or closed; to provide conveniently releasable means for securely holding both doors of the pair in an exact predetermined open position; to provide a mechanism that will continue to operate satisfactorily without adjustment over a long period of service, regardless of looseness of fit of joints incident to normal wear; to provide an automatic latch which is controlled by the movement of the manually operated door so as to lock the opposite or mechanically operated door when the latter has reached closed position, the said latch being released by the opening movement of the manually operated door; to provide means permitting the manually operated door to be swung open sufficiently far to allow a person to pass while the latched door remains closed, thereby insuring access to the mechanism in the event of any derangement thereof; to provide a mechanism which may be associated with the doors so as to apply the necessary forces thereto at points reducing to a minimum the reaction forces in the doors and their supporting hinges; to provide a construction of a character affording a maximum unobstructed doorway when the doors are open; to provide means for timing the relative movement of the doors so that the manually operated one opens in advance of the other and closes after it, thus avoiding any interference between the doors; to provide a mechanism that may be readily applied to any door frame of usual construction; to afford a construction preventing violent slamming of the doors by the force of the wind when the doors are allowed to stand in partially opened position; to provide a single mechanism the parts of which are adapted to be assembled so as to accommodate it for application to doors of different size; and to provide a mechanism permitting variation in the angle between the plane of either fully opened door and the plane of the door opening.

Generally stated, the principal feature of the invention consists in providing the door controlling mechanism with a plurality of door braces or stays, each cooperating with one of a pair of swinging doors and each comprising a plurality of hingedly connected members, and in operative-

ly interposing between said hinged braces means for communicating movement from one to the other thereof, the parts being so combined and related that the movement of one door to fully opened or fully closed position automatically causes the other door to be fully opened or closed, as the case may be, but at a different rate, one door remaining stationary in closed position during the initial opening movement of the other and reaching closed position ahead of the latter when the doors are being shut.

Another feature of the invention consists in affording means for locking one door to the door frame in closed position and in providing means governed by the movements of the other door for automatically releasing such door locking means.

A further feature of the invention consists in forming the door controlling mechanism with door stays each comprising a plurality of movably connected members, said stays being pivotally connected to the respective doors and pivotally connected to the head of the door frame with which the pair of swinging doors is associated, and in operatively connecting said stays by a system of links and levers affording lost motion between the stays, whereby one door is opened and closed by the manual movement of the other but in a manner permitting the manually operated door to be partially opened in advance of the other door and to close last.

Other features of the invention arising from advantageous forms and relations of the parts of the mechanism will hereinafter appear and be particularly pointed out in the claims.

In the drawings illustrating a preferred form of the invention:

Figure 1 is an inverted plan view of the door controlling mechanism as applied to a pair of outwardly swinging doors, the position of the various parts when the doors are fully opened being shown in full lines, the initial closing movement of the manually operated door which occurs prior to the closing movement of the other door being shown in dot and dash lines, and the manner of adjusting the parts to control the extent of opening of the doors being indicated in dotted lines at the right hand end of the view.

Figure 2 is an inverted plan view of the mechanism, showing in full lines the positions assumed by the parts when the doors are fully closed, and showing in dot and dash lines the position which the manually operated door occupies when the other door reaches fully closed position.

Figure 3 is an inverted detail elevational view of one hinged stay arm and the cooperating adja-

cent parts, the plane of the view being indicated by the line 3—3, Figure 1.

Figure 4 is a sectional view on the line 4—4, Figure 3.

5 Figure 5 is a bottom detail view of the locking mechanism and adjacent parts, showing the relative positions assumed when both doors are closed.

10 Figure 6 is a horizontal sectional view of the parts shown in Figure 5, but illustrating the positions assumed by the parts when the door by which the locking mechanism is controlled has been opened to the position shown in dot and dash lines in Figure 2.

15 Figure 7 is a detail sectional view on the line 7—7, Figure 5.

Figure 8 is a detail view, partly in vertical section and partly in inverted elevation, of the central oscillating lever and its mounting together 20 with portions of the links connecting the lever to the door stays.

Figure 9 is a detail perspective view of the latch member for locking one of the doors in closed position.

25 Figure 10 is a detail sectional view on the line 10—10, Figure 5.

Figure 11 is a detail sectional view on the line 11—11, Figure 3.

30 Figure 12 is a detail view, partly in section, showing a preferred form of stay arm and connecting bracket for the manually operated door.

Figure 13 is a detail view, partly in section, showing a preferred form of stay arm and connecting bracket for the door controlled by the 35 manually operated door.

Figure 14 is a view corresponding to Figure 3 but illustrating a modified form of the hinged stay arm construction.

Figure 15 is a bottom view of the modified form 40 of the device shown in Figure 14.

Figures 16, 17, 18 and 19 are detail sectional views respectively taken on the lines 16—16, 17—17, 18—18 and 19—19, Figure 14.

45 In the drawings 1 and 2 respectively are swinging doors each of which is connected to the door frame by hinges 3. Manual operation of the door 1 controls the door 2 through the instrumentality of the door controlling mechanism by which both doors are operatively connected.

50 The operating parts of the door controlling mechanism are supported from a stationary plate or bracket 4 which is secured by screws or other suitable means to the underside of the lintel 5 of the door frame in the middle of the doorway.

55 Rigidly secured to the supporting plate 4 are three downwardly extending spaced studs or pintles 6, 7 and 8 respectively, the intermediate pinte 6 occupying a fixed position in the exact center of the door opening for all applications of the mechanism to any pair of hinged doors, and the positions of the pintles 7 and 8 being dictated by variations in the width of the door opening and by the angle of rotation it is desired the door shall have before coming to rest in fully open position. As clearly shown in Figures 1, 2, 5 and 6, the supporting plate 4 is provided at its ends with a series of openings 9 for receiving the pivot pins 7 and 8, thus permitting the latter to be positioned at various distances from the central stud 6. The studs 6, 7 and 8 which are of reduced diameter at their upper ends are preferably secured to the supporting plate 4 by means of nuts 10, as shown in Figures 8 and 14. The series of regularly spaced holes 9 at the ends of the supporting plate 4 enables the outer studs 7 and 8 to

be adjusted as required to suit various widths of door openings and such change in location of these pivot studs is also one of the adjustments controlling the angle of outward rotation of the door. This latter adjustment, as applied to door 5 2, is illustrated in dotted lines in Figure 1.

The doors 1 and 2 are provided with folding stays 11 and 12 respectively which are generally similar although differing somewhat in detail. Each stay is hinged near its center of length, as 10 indicated at 13, and is pivotally connected at its outer end, at 14, to a bracket 15 rigidly secured to the inner face of the neighboring door. The brackets 15 are preferably alike and may advantageously be made of channel form. The jointed 15 stay 11 adjacent the door 1 is pivotally mounted at its inner end upon the downwardly projecting pinte or stud 7, while the brace or stay 12 for the door 2 is similarly pivotally mounted at its inner end upon the stud 8, the stays being free to rotate at their outer ends on the pivots 14 carried by the door brackets and being free to rotate at their inner ends on the respective pintles 7 and 8 projecting downwardly from the supporting plate 4. Each of the stays 11 and 12 comprises a 25 link member and a lever member, the link member being pivotally connected to the door and the lever member being pivotally mounted upon the appropriate stud 7 or 8 as the case may be. The link members preferably are of channel cross section for the major portion of their length, while the lever members are of angular form between their ends. Each stay is provided with a central stop formed by the extension of one of the members beyond the hinge point 13, as indicated at 35 20 in Figures 1, 3 and 4. These stops respectively limit the rotation of the arms or links 16 and 18 around their pivotal points 14 when the doors have reached the full open position. The parts are so related that when the stop 20 on the lever 40 member 17 engages with the link 16, the hinge point 13 has passed beyond the straight line extending from the pivot stud 7 to the pivot point 14 on the door 1, thus causing the hinged stay 11 to act as a compression strut or brace between 45 the door 1 and the door frame and thereby serving to hold the door open against any force tending to accidentally move it towards closed position. The stop 20 carried by the lever member 19 of the stay 12 cooperating with the other door 50 acts in a similar manner to cause the jointed stay 12 to operate as a brace or strut for preventing an accidental closing movement of the door 2. Springs 21 which are respectively connected to the link members 16 and 18 and to the door brackets 55 15 adjacent thereto function, as the doors approach full open position, constantly to exert upon the links to which they are connected force necessary to carry the hinge points 13 of the door stays beyond the straight line connecting pivotal 60 points at the ends of the stays and serve to maintain the members of the stays 11 and 12 in positive strut relation until rotated by a greater outside force overcoming the action of the springs. The tension springs acting between the stay arms 65 and the door brackets snap the stays independently into final strut position since there is no rigid connection between the stays in this position of the parts. The outer end of the link or arm 16 may advantageously be flattened or formed 70 eccentric to the pivot pin 14, as indicated at 22 in Fig. 12, and the outer end of the link 18 may likewise be flattened or formed eccentric to its pivot pin, as indicated at 23 in Fig. 13. The outer ends of the links 16 and 18 thus provide stops 75 78

which by engaging with the respectively neighboring door brackets 15 prevent these parts from collapsing so as to permit the springs to become disassembled when the device is not mounted on 5 the doors.

As a convenient means for manually releasing the stay 11 of the door 1 so as to permit said door to be closed, a flexible pull, such as a chain or cord 24, is preferably employed (see Fig. 1). The 10 flexible pull member is attached at one end to the stay arm 16 between the pivotal points 13 and 14 of the latter, then passes horizontally over a pulley 25 mounted on the inside of the door 1 and then hangs vertically downward for a distance 15 enabling it to be conveniently grasped by the operator. By pulling upon the flexible member 24 the spring 21 holding the brace 11 in strut position is overcome and the hinge joint 13 of the brace is shifted toward the door, thus permitting 20 the stay 11 to fold when a manual force is applied to the door 1 to close the latter. As will hereinafter appear, the folding brace 12 for the door 2 is automatically released as the door 1 is moved towards closed position.

The lever member 17 of the folding stay 11 is of bell crank form, its shorter arm 26 preferably being fashioned as a plate which is rigidly secured to the longer arm. The lever 19 of the folding stay 12 for the door 2 likewise is in effect 30 a bell crank lever, but the construction is such that a certain amount of slack or lost motion is provided between the two arms of the lever. This is preferably accomplished by forming the shorter arm of the lever 19 as a plate or quadrant 27 which 35 is pivotally mounted on the stud 8 and is provided with a tongue or yoke 28 spaced from the body of the plate so as to form an elongated slot through which the longer arm of the lever 19 passes. The outer end of the slot is closed, preferably by a 40 bolt 29, to form a stop for limiting the lost motion between the arms of the lever 19 to a predetermined amount in one direction. The extent of lost motion in the other direction is controlled by the stop 30 formed by the junction of the yoke 45 28 with the body of the plate forming the short arm of the lever 19. As will be readily understood, after the shorter arm or quadrant 27 of the lever 19 has rotated in either direction a sufficient amount to bring one or the other of the 50 stops 29 and 30 into contact with the longer arm of the lever both arms rotate together upon the pivotal stud 8.

To transmit the manually applied forces from the door 1 to the door 2, both in opening and 55 closing the doors, the folding stays 11 and 12 are operatively connected by an intervening link and lever system comprising an oscillating lever 31 pivotally mounted at the center upon the central stud or pintle 6 and a plurality of links 32 60 respectively connecting the shorter arms of the levers 17 and 19 to said lever 31. The inner ends of the links 32 are respectively pivoted at 33 to the opposite ends of the oscillating lever 31 and are respectively pivoted to the shorter arms 26 65 and 27 of the lever members of the door stays, as indicated at 34. The links 32 are preferably formed as a pair of plates receiving between them the shorter arms 26 and 27 of the respective lever members of the folding struts. Each 70 of the link members 32 is provided towards one end with a series of holes 35, the links being so positioned during the assembly of the mechanism that the series of holes for the link 32 adjacent the door 1 may receive the pivot pin 33, 75 while the series of holes in the link nearer the

door 2 may receive the pivot pin 34 associated with the oscillating quadrant 27. The series of pivot pin openings 35 in the links 32, in conjunction with the series of openings 9 in the supporting plate or bracket 4, provides means for 5 adjusting the mechanism to various widths of door openings and also enables the extent of angular opening movement of the doors to be controlled. If, for example, the stud 8 is moved to an opening 9 which is two holes nearer the 10 door jamb to which the door 2 is hinged and the pin 33 farthest from the door 2 is positioned two holes nearer the free end of the link 32 with which it cooperates, and the door bracket 15 is shifted correspondingly nearer the hinged 15 side of the door, the door 2 will assume the more widely opened position illustrated in dotted lines in Fig. 1. By corresponding adjustments the extent of angular opening movement of the door 1 may also be varied. 20

The door controlling mechanism preferably embodies means for automatically locking the door 2 in closed position and for automatically releasing said door from such locking means when the door 1 is manually opened a sufficient distance. 25 For this purpose a hook-shaped latch 36 is pivotally mounted at 37 on the door bracket 15 carried by the door 2. The adjacent spring 21 attached to the link 18 of the folding brace 12 is connected to the latch 36 at 38 to yieldingly 30 hold the latch in door locking relation to the bracket 15 upon which it is mounted. As is shown in Figure 5, when the door 2 is fully closed the latch 36 hooks around the downwardly projecting stud 8 carried by the stationary support- 35 ing plate 4 secured to the door jamb thus locking the door 2. During the closing movement of the door the inclined or cam surface 39 of the latch cooperates with the stud 8 so as to cause the latch to perform the slight unlocking rotation 40 necessary to allow it to clear the stud before moving to locked position. To effect the automatic release of the latch 36 the pivoted quadrant 27 forming the shorter arm of the lever 19 is provided with a vertically extending lug or 45 post 48 which, during the initial opening movement of the door 1 presses outwardly against the extended end or finger 41 of the latch and thereby causes the latter to perform an unlocking rotation against the tension of the spring 21 act- 50 ing upon it. The hooked end of the latch 36 is thus disengaged from the stationary stud 8 and the door 2 is unlocked.

The operation of the device is very simple. Assuming both doors to be closed, the operator 55 merely pulls upon the door 1 so as to move it to full open position. The force manually applied to the door 1 to open it is communicated to the door 2, through the link 16 to the bell crank lever 17, and thence to the adjacent link 32 pivotally 60 connected to the central oscillating lever 31. The ensuing rotation of the lever 31 upon its pintle 6 causes the other link 32 to impart a rotary movement to the quadrant 27 pivotally mounted on the stud 8. Because of the lost motion be- 65 tween the quadrant 27 and the longer arm of the lever 19, the initial rotation of the quadrant upon the stationary stud 8 effects no movement of the door 2. By this initial rotation of the quadrant, however, the post or finger 48 is 70 caused to press against the extension or tail 41 of the latch 36 and thus rotate the latch out of locking engagement with the stationary stud 8. When the door opening rotation of the quadrant 27 has taken up all the lost motion 75

between the quadrant and the longer arm of the lever 19 the latter rotates upon the stud 8 and thereby communicates motion to the link 18 to which it is pivotally connected, thereby forcing the door 2 to open position. When in full open position, as has been heretofore pointed out, the hinge points 13 of the folding stays 11 and 12 have passed to the inside of the line connecting the end pivots of the respective stays, and the doors are therefore prevented from accidentally swinging toward closed position. In closing the doors the operator applies tension to the flexible pull 24 to shift the position of the hinge point 13 of the folding stay 11 to door releasing position, as heretofore described. By then pushing inwardly upon the door 1 force is transmitted from the latter to the link 16 and thence to the bell crank 17, thereby causing the adjacent link 32 to push upon the oscillating lever 31 and effect a rotation of the latter. This rotation of the lever 31 is communicated to the quadrant 27 through the intervening link 32 and causes the latter to rotate until the stop 30 thereof comes into contact with the long arm of the lever 19. As soon as this occurs the long arm of the lever 19 rotates upon the stud 8 and shifts the hinge point 13 of the folding stay 12 toward the door 2 and across the line connecting the stud 8 with the pivot pin 14 at the outer end of the folding stay 12. The continued rotation of the lever 12 thereupon results in pulling upon the link 18 with the consequent closing of the door 2.

When both doors are braced open the long arm of the lever 19 forming a part of the folding brace 35 12 for the door 2 is not in contact either with the stop 29 or with the stop 30 of the quadrant 27. The clearance or lost motion thus afforded avoids the necessity of providing or maintaining the nice adjustment of parts that would otherwise 40 be required to bring both folding stay arms 11 and 12 into strut position at exactly the same time. The lost motion in the mechanism also enters into the action of the device as the door 1 reaches closing position. Upon comparing Figure 1 with Figure 2 it will be noted that in closing 45 the doors the lever 17 of the folding brace for the door 1 rotates through a greater angle than the long arm of the lever 19 of the folding brace 12 for the door 2. This is effected by locating 50 the hinge point 13 of the stay 11 at a distance from the pintle 7 which is somewhat less than the distance between the pintle 8 and the hinge point 13 of the folding stay 12 for the door 2. The effect of this difference is to make the closing 55 action of the door 2 faster than that of the door 1, so that door 2 is fully closed before door 1 closes. The point at which the door 2 reaches full closed position corresponds to the position 60 of the parts when the pin 34 connecting the link 32 to the lever 17 comes into alignment with the stationary stud 7 and the pivot pin 33 which is at the end of the oscillating lever 31 nearer the door 1. It will be appreciated that as the door 1 continues its closing movement after the door 2 65 has reached full closed position, a slight reverse movement occurs in the links 32, the oscillating lever 31 and in the quadrant member 27, but due to the lost motion between the quadrant and the long arm of the lever 19 the door 2 is not 70 re-opened by this action.

The modified form of construction illustrated in Figures 14 to 19 inclusive is the same as that heretofore described except that the members forming the hinged door stays are somewhat differently constructed. Only the door stay 11a

immediately adjacent the door 1 is illustrated, but it will be understood that the folding stay for the door 2 may be of a similar nature. As in the construction heretofore described the stay or brace 11a consists of a link member 16a and a lever member 17a which are hinged together by a bolt 13 which passes through a short sleeve 42 lying between oppositely disposed washers 43 through which the bolt also extends. The sleeve or spacer 42 passes through both of the members 16a and 17a of the brace 11a and is of such length that the washers are prevented from binding against said members, thus permitting them to hinge freely. The link member 16a of the brace is of angle form in cross-section adjacent the hinge point 13 and is of channel form adjacent the door. The lever member 17a is also of angle form adjacent the hinge point 13, the portions of angle section being nested together as well illustrated in Figure 16. The member 17a extends beyond the hinge point 13 toward the door 1 so that its vertical leg cooperates with the vertical leg of the member 16a to form a stop for limiting rotation of the parts when the members of the stay 11a are in the strut position. To prevent the members 16a and 17a from buckling vertically at the hinge point when the stay 11a is operating to maintain the door in open position, a short sleeve 44 and washer 45 are firmly secured to the link 16a by a rivet 46, the space between the washer 45 and the adjacent leg of the link 16a being sufficient to receive the outer end portion 47 of the horizontal leg of the lever member 17a. In ordinary operation there is no contact between the outer end of the lever arm 17a and the washer 45, but in case of unusual compression being applied to the brace 11a, buckling out of the horizontal plane is prevented by contact with the washer. To afford clearance for the sleeve 44 when the members 16a and 17a of the folding brace occupy the relative positions they assume when the door 1 is closed, the lever member 17a is notched or recessed as indicated at 48. Other features of construction being like those heretofore described have been indicated by corresponding reference numerals.

I claim:

1. A door controlling mechanism for connecting a pair of swinging doors to cause one door to operate the other, said mechanism involving a plurality of hinged door stays each pivotally connected to one of the doors and each comprising a link member and a lever member, each of said lever members being adapted to be pivotally mounted on the head of the door frame, said pivotal points of the lever members being in spaced relation, an oscillating lever pivotally mounted on the head of the door frame, and links movably connected to said oscillating lever on opposite sides of the pivotal point of the latter, said links being respectively connected to said lever members of said door stays.

2. A door controlling mechanism for connecting a pair of swinging doors to cause one door to operate the other, said mechanism involving a plurality of door stays each comprising a plurality of pivotally connected members, one of the members of each stay being pivotally connected to the door adjacent thereto, means for operatively connecting said stays to cause one of them when actuated by a swinging movement of the door adjacent thereto to operate the other stay to effect a swinging movement of the other door, stop means for each of said stays to limit rela- 75

tive movement of said pivotally connected stay members in one direction when said stay members act as struts to maintain the doors in open position, yielding means for maintaining said

5 stays in strut position, and means for releasing one of said stays from the control of the said yielding means cooperating therewith to permit a closing movement of the adjacent door.

3. A door controlling mechanism for connecting 10 a pair of swinging doors to cause one door to operate the other, said mechanism involving a plurality of door stays each comprising a plurality of pivotally connected members, one of the

15 members of each stay being pivotally connected to the door adjacent thereto, means for operatively connecting said stays to cause one of them to operate the other, stop means respectively associated with said stays for limiting relative move-

20 ment of said pivotally connected stay members in one direction when said stay members are in position for preventing accidental closing of the doors, means associated with said stays for yield-

25 ingly opposing relative movement of said pivotally connected stay members in the other direction when said stay members are in position for maintaining the doors in open position, and

means for releasing one of said stays from the control of the said yielding means cooperating therewith, said means for operatively connect-

26 ing said stays including means for automatically releasing one of said stays from the control of the said yielding means cooperating therewith.

4. A door controlling mechanism for connecting 30 a pair of swinging doors to cause one door to operate the other, said mechanism involving a plurality of hinged devices respectively pivoted

35 to the doors and each comprising a link member and a bell crank lever, said levers being mounted on spaced stationary pivots and the arms of one

40 of said levers having a lost motion connection between them, and means for operatively connecting said levers.

5. A door controlling mechanism for connecting 45 a pair of swinging doors to cause one door to operate the other, said mechanism involving a plurality of hinged door stays respectively pivoted to the doors and each including a pivotally mounted lever member, the points of pivotal

50 mounting of said lever members being stationary and spaced from each other, means for operatively connecting said lever members to permit one of said stay devices to operate the other stay device, means cooperating with and movable with respect to the door to which said last named stay

55 device is pivotally connected for locking said last named door in closed position, and means movable by one of said staying devices upon an opening movement of the other door for releasing said locking means to permit an opening movement

60 of the door upon which said locking means is mounted.

6. A door controlling mechanism for connecting 55 a pair of swinging doors to cause one door to operate the other, said mechanism involving a plurality of links each pivotally connected to one of said doors, a plurality of levers each pivotally connected to one of said links, each of said

65 levers being pivotally mounted with their pivotal points in spaced relation, a pivotally mounted oscillating lever, the pivotal point of said oscillating lever being spaced from the pivotal points of the levers first named, and a plurality of link devices respectively connecting each of said

70 first named levers to said oscillating lever, the pivotal points of said several levers being ar-

ranged in the form of a triangle and each of said link devices being pivotally connected to said oscillating lever with their points of pivotal connection disposed in spaced relation.

7. A door controlling mechanism for connecting 10 a pair of swinging doors to cause one door to operate the other, said mechanism involving a plurality of links each pivotally connected to one of said doors, a plurality of bell crank levers each having a fixed pivotal point and each being 15 pivotally connected to one of said links, the shorter arm of one of said bell crank levers having a lost motion connection with the longer arm of its lever, and means for operatively connecting said bell crank levers to cause them to ro- 20 tate in opposite directions when the link connected to one of them is actuated by the movement of the adjacent door.

8. A door controlling mechanism for connecting 25 a pair of swinging doors, said mechanism in-

cluding means for preventing accidental closing of said doors involving a plurality of door stay devices each movably connected to one of the

30 doors, each of said stay devices constituting means for independently bracing in fixed open position the door with which it is associated,

means operatively associated with each stay de-

vice causing it to assume bracing position and lost motion means for operatively connecting said

35 stay devices, one of said stay devices being adapted to actuate said lost motion means to thereby actuate the other stay device when force is applied to one door, and said lost motion means permitting an initial opening movement of one

40 of said doors while the other door remains sta- 45 tionary.

9. A door controlling mechanism for connecting 50 a pair of swinging doors to cause one door to operate the other, said mechanism including a plurality of door staying devices each movably connected to one of said doors, each of said stay-

55 ing devices involving a plurality of pivotally connected members constituting independent means for bracing its associated door in open position,

means for causing each staying device to assume 60 bracing position, means operatively interposed between said staying devices for causing one of

65 said devices to actuate the other, said last named means involving a plurality of pivoted members providing a lost motion connection between said

70 door staying devices permitting one of said doors to execute initial opening and closing movements while the other door remains stationary, and

75 means fixed with respect to the door frame affording an immovable pivotal support for one end of one of said first named members.

10. A door controlling mechanism for connecting 80 a pair of swinging doors to cause one door to operate the other, said mechanism involving a plurality of relatively movable members consti-

85 tuting a lost motion connection between the doors permitting one of said doors to execute an initial

90 swinging movement while the other door remains stationary, said members including a plurality of

95 links and a plurality of levers and constituting means adapted to be actuated by one door to cause the other door to open last and close first,

100 and said means being so correlated as to constitute means for positively preventing the first named door from closing before the last named door has reached its fully closed position.

11. A door controlling mechanism for connecting 105 a pair of swinging doors to cause one door to operate the other, said mechanism involving a

110 plurality of relatively movable members consti-

tuting a lost motion connection between the doors permitting one of said doors to execute an initial swinging movement while the other door remains stationary, said members including a plurality of links and a plurality of levers and constituting means adapted to be actuated by one door to cause the other door to open last and close first, and also constituting means for preventing the first named door from being closed before the last named door has reached full closed position, means for independently locking the last named door, and means associated with and actuated by said movable members for shifting said locking means to door releasing position after the first named door has been partially opened.

12. A door controlling mechanism for connecting a pair of swinging doors to cause one door to operate the other, said mechanism involving a plurality of hinged devices each pivotally connected to one of said doors, means for operatively connecting said hinged devices to cause one to operate the other upon a swinging movement of

one of said doors, and means for locking one of said doors in closed position, one of the pivotally hinged devices being provided with means actuated upon an opening movement of one door to release said locking means.

13. A door controlling mechanism for connecting a pair of swinging doors to cause one door to operate the other, said mechanism involving a plurality of links each movably connected to one of said doors, a plurality of levers respectively connected to said doors by said links, and a plurality of spaced pivots fixed with respect to the door frame and respectively forming pivotal mountings for said levers, and means for causing one of said levers when moved by the door to 15 which it is connected to actuate the other lever, said means movably connecting said levers and constituting a lost motion connection between said levers enabling one of said levers to be actuated by the door to which it is connected while 20 the other door remains stationary.

CHARLES F. SPONSLER.
